(57) **CLAIM**

The ornamental design for a cleaning device for enteral fluid couplings, substantially as shown and described.

DESCRIPTION

FIG. 1 is a first perspective view of the cleaning device for enteral fluid couplings according to the design.

FIG. 2 is a second perspective view of the cleaning device of FIG. 1.

FIG. 3 is a first side view of the cleaning device of FIG. 1, the opposite side view being substantially identical.

FIG. 4 is a top view of the cleaning device of FIG. 1, the bottom view being substantially identical.

FIG. 5 is a first end view of the cleaning device of FIG. 1; and,

FIG. 6 is a second end view of the cleaning device of FIG. 1.

Portions shown in broken lines are for illustrative purposes only and form no part of the claimed design.

1 Claim, 2 Drawing Sheets
